(57) **CLAIM**

The ornamental design for a seat with arms and legs, as shown and described.

DESCRIPTION

FIG. 1 is a top, front, right side perspective view of a seat with arms and legs of the new design;

FIG. 2 is a top, front, right side perspective view thereof, with the seat bottom and arms shown in a folded up position;

FIG. 3 is front elevation view of thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines are shown for illustrative purposes and form no part of the claimed design. The seat with arms and legs is shown with a symbolic break in its length. The appearance of any portion of the article between the break lines forms no part of the claimed design.

1 Claim, 4 Drawing Sheets
